UNITED STATES PATENT OFFICE.

EDWIN V. WINGARD, OF LOUISVILLE, KENTUCKY.

IMPROVEMENT IN BRICK-KILNS.

Specification forming part of Letters Patent No. 154,310, dated August 18, 1874; application filed July 11, 1874.

To all whom it may concern:

Be it known that I, EDWIN V. WINGARD, of Louisville, in the county of Jefferson and State of Kentucky, have invented a new and valuable Improvement in Calorific Kilns; and I do hereby declare that the following is a full, clear, and exact description of the construction and operation of the same, reference being had to the annexed drawings, making a part of this specification, and to the letters and figures of reference marked thereon.

Figure 1 of the drawing is a representation of a front view of my kiln. Fig. 2 is a longitudinal vertical sectional view, and Figs. 3 and 4 are detail sectional views, of the same. Fig. 5 is a transverse vertical sectional view, and Fig. 6 is a detail view.

This invention has relation to kilns, which are designed for burning or glazing any object made of clay; and my objects are mainly to so contrive a kiln, of rectangular or other shape, that the temperature is under complete control of the attendants, and may be increased or diminished according as the material to be burned may require; also, to provide pipes or flues and other passages in the furnace-walls, the walls of gas-vaults, and the walls of the kiln proper, through which flues or passages air is conducted into the flame-spaces for the purpose of mixing with the carbureted hydrogen and unconsumed gas from the furnaces, and thereby supplying oxygen and promoting combustion of the gases, as will be hereinafter explained.

In the annexed drawings, I have represented a rectangular kiln, but I contemplate the application of my improvement to circular and polygonal kilns.

The walls A are constructed of any material which will resist the fire. The kiln-walls may be made of any desired thickness. I prefer from two and a half to three bricks at the base, tapering off, as the wall rises, to nine inches at the coping. Through the walls A, at their bases, are irregular openings c, communicating with the gas-vault C, which are constructed so as to carry into the kiln and distribute equally the inflamed gases. Each of these openings is provided with a passage, d, passing upwardly at an angle, through the wall, to the top of the upper surface of the

vault C, as shown in Fig. 4, which passage allows finely-pulverized ashes, sand, brick-dust, or other refractory substances to be introduced into the openings c for the purpose of partly or wholly closing them, according to the heat required, sometimes entirely closing the passage c to shut off the heat when the contents of a chamber have been sufficiently burned. Along the outside of the main walls are constructed the separated gas-distributing vaults C, and outside of and supporting these vaults are constructed heat or gas generating furnaces D. These furnaces are so spaced and arranged with respect to the separated vaults C as to furnish each particular part of the kiln with any desired quantity of heat. Each furnace is constructed with air-chambers f', with damper-holes f" outside and jet-holes i inside. The external air is admitted into the chambers f', where it is highly heated, and conducted into the furnace amongst the incandescent fuel for the purpose of increasing combustion. In order to supply the carbureted-hydrogen gas with oxygen from the atmosphere in proper quantities, and have the temperature in the kiln such that the glazing material, bricks, or wares, or the layers that contain them, shall not be damaged by sudden changes of temperature, I carry atmospheric air into the body of the kiln through flues d', arranged far enough below the surface of the ground to avoid melting them. I also carry atmospheric air through the walls A, under the gas-vaults, as shown by the passage g, Fig. 3, and introduce this air into the upper portion of the gas-vaults through small openings. I also carry air into the walls A, between the gas-generating furnaces, taking the air up through flues h, and conducting it into the vaults C, near the "skew-back" of the arch, thus supplying the vault with air in such quantities as may be desired. J J designate pipes, which are thickly perforated, and arranged horizontally over the body of the kiln. These pipes communicate with an imperforated pipe, J', which leads down to a suitable exhausting-engine (not shown) for the purpose of drawing the heated air and gases from the top of the kiln, and forcing the heat whithersoever it may be required.

It will be seen, by reference to Fig. 5, that

the kiln is divided by walls G into several apartments, each apartment being provided with large and small eyes or passages c, and also with a gas-vault, C, and a furnace, D. I am thus able to control the fires in each part of the kiln. The walls G are made of green bricks.

The operation of my kiln is as follows: The division-walls are extended nearly to the top of the kiln, after which the kiln is filled with bricks to be burned, the bricks being locked together over said division. I thus have the kiln divided into compartments, in number corresponding to the number of furnaces; consequently I am able to regulate the heat and distribute it uniformly in each compartment. When the fires are made in the furnaces D, the heated products pass into the vaults C, and are therein mixed with heated air, which enters them at their highest points. This mixture of the gases and air insures a perfect combustion, and a pure flame issues through the passages c, which are regulated by introducing more or less finely-pulverized ashes, sand, brickdust, or refractory material into said passages c through the inclined chutes d. The vaults C afford good supports for the kiln-walls, and the furnaces also support these walls, and the vaults, by this arrangement of the vaults and furnaces, allow the air and gases to be thoroughly mixed before being admitted to the brick-kiln proper. In burning bricks and various kinds of wares it is necessary, in order to prevent their being broken, that cool air should be entirely excluded from the kiln. This I do most effectually by arranging the mixing-vaults outside of the kiln and heating the air before introducing it into the kiln through the flame-passages c. I also introduce cool air into the bottom of the kiln in regulated quantities, by means of the passages d', which are arranged beneath the furnaces and the vaults C. This supplies the flame inside of the kiln with oxygen, and keeps up a lively combustion therein.

Heretofore it has been customary in lime-kilns to simultaneously force fresh air through the fuel into the kiln, for the purpose of igniting or burning the fuel and cooling the burnt lime as it falls in the kiln.

I am aware that it is not new to place furnaces beneath the floor of a kiln and cause the heated gases and products of combustion to pass beneath such floor to the back of the kiln, and thence upwardly between the back wall and a partition, to a vaulted roof and into a burning-chamber, from which they finally escape through uptakes at the front. I am also aware that a kiln in which the flame and heated gases from the furnaces pass in a downward direction through the ware in the burning-chamber is not new, nor is it herein claimed; also that the employment of pipes, arranged over the kiln to utilize the heat which escapes from the kiln, is not new; also, that carrying air into the body of the kiln, through flues arranged below the furnace, is not new.

What I claim as new, and desire to secure by Letters Patent, is—

1. In a kiln, the combination of the furnace D, having air-chambers f and jet-holes i, and a gas-distributing vault, C, having air-passages g and air-flues h, substantially as specified.
2. In combination with the furnace of a burning-kiln, the air-chambers f, damper-holes f', and jet-holes i, substantially as and for the purpose set forth.
3. In a kiln, the combination of the air-passage g, passing under the gas-vault C and extending into the upper portion of the said gas-vault, and the air-flues h, communicating with the vault C near the "skew-back" of the arch; substantially as and for the purpose described.
4. The combination, with a kiln, of the passage d, for the introduction of sand or other comminuted refractory material, for the purpose of partially or wholly closing the gas-openings c communicating with the vault and kiln.

In testimony that I claim the above I have hereunto subscribed my name in the presence of two witnesses.

E. V. WINGARD.
